CERAMIC MOLDING PRESS

George L. Cherry, Western Springs, and Charles C. Veale, Wheaton, Ill., assignors to Western Electric Company, Incorporated, New York, N. Y., a corporation of New York

Application August 10, 1943, Serial No. 498,078

2 Claims. (Cl. 25—91)

1

This invention relates to ceramic molding apparatus and more particularly to an apparatus for making slugs of ceramic material, to be later extruded in the forming of articles.

It is an object of the present invention to provide a simple molding apparatus for quickly forming articles.

In accordance with one embodiment of the invention, a slug, to be later extruded in the process of forming ceramic articles, is compressed between a pair of molding plungers positioned along a single axis and movable in a compressing cylinder and wherein one of the rams is driven differentially to quickly move to position after a supply of material has been placed in the cylinder. The operation of the apparatus may be initiated by closing a guard member surrounding one of the compressing plungers, thereby to set in operation a fluid pressure system to move the upper of the two rams into the compressing cylinder. Automatically operable means are provided to evacuate the compression chamber when the upper ram moves to position in the compressing cylinder.

A better understanding of the invention may be had by reference to the following detailed description when considered in conjunction with the accompanying drawings, wherein

Fig. 1 is a front elevational view on a relatively small scale of an apparatus embodying the invention;

Fig. 2 is a transverse vertical sectional view taken substantially along the line 2—2 of Fig. 1 in the direction of the arrows, parts being broken away to conserve space and both Figs. 1 and 2 showing the rams in their inoperative position with the movable guard member open;

Fig. 3 is a horizontal sectional view taken substantially along the line 3—3 of Fig. 1 in the direction of the arrows and showing details of the guard mechanism and means whereby material may be deposited in the apparatus;

Fig. 4 is an irregular fragmentary vertical sectional view taken substantially along the line 4—4 of Fig. 3 in the direction of the arrows showing details of construction of the compressing or molding cylinder and the upper ram;

Fig. 5 is a fragmentary detail sectional view taken substantially along the line 5—5 of Fig. 3 in the direction of the arrows showing some details of construction of a hopper provided for feeding ceramic material into the molding cylinder; and

Fig. 6 is a schematic diagram of the fluid pressure circuit of the apparatus showing the com-

2

pressing rams in their operative positions and showing the various valves for controlling the rams in their operative positions.

Referring to the drawings, wherein like reference characters designate the same parts throughout the several views, particular reference being first had to Figs. 1 and 2, a base casting 10 is provided with a flat bottom portion 11, a flange portion 12, and a cylinder portion 13. This casting serves to support the entire apparatus. Standards 14 and 15, having reduced shanks 16 and 17, respectively, which are threaded to receive retainer nuts 18 and 19, extend through the flange portion 12 and are attached thereto by means of the retainer nuts. The standards 14 and 15 are also reduced at their upper ends, as shown at 20, to receive a mold supporting block or bolster 21. The block 21 has a shouldered aperture 22 formed in it, in which a mold chamber 23 may be fixed by means of machine screws 24—24. The mold chamber is adapted to receive a cylindrical ram 25, which is mounted upon an upper end of a piston rod 26. The piston rod 26 is suitably attached to a piston 27, slidable in the cylinder portion 13 of the base casting 10, suitable packing glands 28 and 29 being mounted to encircle the piston rod 26 and seal the lower end of the mold chamber 23 and a cylinder cap 30, respectively, the cylinder cap being suitably mounted to close the upper end of the cylinder portion 13. The cylinder portion 13 of the base casting 10 has an internal shoulder 31, against which the piston 27 will strike when the piston is moved to its lower position and the cylinder portion 13 has an aperture 32 in which the end of a pipe 33 is threaded. Similarly, the cylinder cap 30 is provided with an entrance aperture or port 34, into which a pipe 35 is threaded.

From the foregoing, it is believed to be apparent that the piston 26 may be raised by feeding a fluid under pressure through the pipe 33 and permitting fluid in the upper portion of the cylinder 13 to escape through the pipe 35, and, in a similar manner, by supplying fluid under pressure through the pipe 35, and permitting the escape of fluid through the pipe 33, the piston 26 may be lowered.

The reduced portions 20 of the standards 14 and 15 which extend above the mold supporting block 21 are surrounded by sleeves 45 and 46, respectively, and on the upper ends of the sleeves there is positioned a cross head 47, which has a cylinder 48 formed integrally with it. The cross head 47 is held in place on the sleeves 45 and 46 by means of two retainer members 49 and 50,

which are threaded onto the ends of the standards 14 and 15. The cylinder 48 is quite similar to the cylinder portion 13 of the base casting 10 in that it has a closure member 51 suitably attached to it, similar to the cylinder cap 30, and the inner surface of the cylinder 48 has an abutment member 52 formed on it for limiting the upward movement of a piston 53. Fluid under pressure may be supplied to the upper end of the cylinder 48 through a pipe 54 and entrance port 55 and may be supplied to the lower end of the cylinder 48 through an entrance port 56 and pipe 57, the port 56 being formed in the closure member 51. A packing gland serves to seal the cylinder 48 against leakage, where a piston rod 58, secured to the piston 53, enters the cylinder through the closure member 51.

By reference to Fig. 4, it will be seen that the piston rod 58 has a head portion 65 formed on it and is provided, as shown in Fig. 3, with diametrically opposed guide portions 66 and 67, which have notches 68 and 69 formed in them for engaging guide rails 70 and 71, which are suitably attached to the sleeves 45 and 46, respectively, and serve to guide the head portion 65 when the piston 58 is reciprocated. Set into the underside of the head portion 65 is an annular resilient gasket 72, adapted to engage the upper surface of the mold chamber 23. The gasket 72 is set into an annular shoulder 73 formed on the head portion concentric with a cylinder closing plunger 74, also with the head portion 65. The plunger 74 and the shoulder 73 define an annular groove 75 extending around the plunger and in communication with a passage 76. The passage 76 is, in turn, in communication with an entrance port 77, which may be closed by a valve comprised of a head 78 and a stem 79. The stem 79 is slideable in an aperture 80 and the head 78 is normally urged to engage a valve seat 81 by a compression spring 82 bearing against a plug 83, in turn threaded into an aperture 84 in the head portion 65. Threaded into the entrance port 77 is a pipe 85 connected to any suitable vacuum pump (not shown), which will tend to draw any air which might be entrapped in the mold chamber 23 out of the mold chamber so that when a mass of ceramic materials 86 is positioned in the mold chamber and pressed between the ram 25 and plunger 74, no air will be trapped in the slug of material formed between the ram and plunger in the mold chamber 23. The plunger 74 is made slightly smaller in diameter than the inside diameter of the chamber 23 to provide a small clearance between the plunger and cylinder to let air pass the plunger but not the granules of ceramic material.

Pivotaly mounted on the mold supporting block 21 at 90 is a bracket 91 (Figs. 1 and 3), which has formed integrally with it an arcuately shaped support 92. The support 92 is attached to a base ring 93, which forms the base of a hopper designated generally by the numeral 94 (Figs. 3 and 5). In addition to the base ring 93, the hopper includes a body portion 95, the lower end of which is tapered to nest in the base ring 93. The bottom end of the hopper 94 is provided with a gate 96 comprised of two plates 97 and 98 attached together by means of machine screws 99 and clamping an annular resilient member 100 between them. The annular resilient member 100 bears against the inner surface of the base ring 93 and normally tends to hold the gate 96 in the position shown in Fig. 5. Set into cooperating notches 101 and 102 formed in the plates 97 and

98 is a square portion 103 of a shaft 104, which is rotatable in opposite sides of the ring 93 and which has a handle 105 fixed to it whereby it may be manipulated. The hopper 94 may be filled with ceramic material to be molded in the apparatus with the gate 96 in the position shown in Fig. 5 and may then be swung into position above the mold chamber 93 and may then be manipulated to drop the ceramic material 86 to the position as shown in Fig. 4 while the rams 25 and 74 are in their retracted position opposite to that shown in Fig. 4.

The rear of the apparatus is enclosed by a guard screen 110, which extends around the rear of the head portion 65 on the piston rod 58 and will prevent anything from being accidentally inserted beneath the ram 74. In addition to the screen 110 guarding the rear of the apparatus, a slidable screen 111 is provided for guarding the front of the apparatus. The screen 111 is provided with four guide rollers 112, 113, 114 and 115 (Figs. 1 and 3), which ride upon guide rails 116 and 117. The guide rails 116 and 117 are mounted at the forward ends of brackets 118 and 119 fixed to the faces of the sleeves 46 and 45, respectively. The guide rail 116, as shown most clearly in Fig. 1, has a pivoted latch 120 pivoted thereon for engaging in a notch 121 when the screen 111 is moved to its lower position, opposite to that shown in Figs. 1 and 2, thus to latch the screen 111 in its downward position. The screen 111 is normally urged to the position shown in Figs. 1 and 2 by a pair of weights 122 and 123, which are interconnected with the screen 111 by a pair of pulley cords 124 and 125, which pass over grooved pulleys 126 and 127 mounted on brackets 128 and 129, respectively, which are, in turn, mounted upon the sleeves 46 and 45, respectively. The screen 111 may be lowered by means of a handle 130 attached thereto and may be latched in its down or closed position by the latch 120.

Fixed to the screen 111 is an actuating arm 140, which extends into the path of arms 141 and 142 of a V-shaped lever 143, which is adapted to control a pilot valve 144 to move the valve to the position shown in Fig. 6 when the screen 111 is moved to its closed position. When the screen 111 is moved to its closed position, the weights 122 and 123 will travel upwardly in guides 134 and 135, respectively, which are attached to the sleeves 46 and 45, respectively.

The pilot valve 144 controls the operation of a main valve 145 (Fig. 6) and is provided with four ports 146, 147, 148 and 149, through which fluid may be directed for controlling the main valve 145. The fluid under pressure is pumped in the direction indicated by the arrow 150 by a pump 151, driven by a motor 152. The pump 151 pumps the fluid under pressure into a main supply pipe 153, which is in communication with the port 149 of the pilot valve 144 and, when the pilot valve 144 is in the position shown in Fig. 6, where the screen 111 is in its closed position, the passageways in the valve 144 will direct the fluid under pressure from port 149 through port 148 to a port 154 in the main valve 145 to shift a slide valve member 155 to the position shown in Fig. 6. The pilot valve 144 in the position shown in Fig. 6 will have its ports 146 and 147 interconnected, whereby the fluid in the left end of the main valve 145 may pass through a port 156 in the main valve, ports 147 and 146 in the pilot valve 144, to a main return pipe 157, which has a main control valve 158 connected in it which may be operated to block the return of fluid from the pump

151, but, when the apparatus is in operation, will be in the position shown in Fig. 6, where the fluid under pressure will be permitted to pass back to the pump 151.

From the foregoing, it will be apparent that when the screen 111 is moved to its closed position, the main valve 145 will be shifted to the position shown in Fig. 6 to direct fluid under pressure entering at a port 158 through a port 159 and thence through pipe 54 to the upper end of cylinder 48, thus tending to drive the piston 53 and plunger 74 downwardly. When the pilot valve 144 is originally operated by the actuating arm 140 due to the closure of the screen 111, ports 159 and 160 of a main valve 161 are interconnected by a slide valve member 162. The slide valve member 162 is normally urged to the position opposite to that shown in Fig. 6, thereby to interconnect the ports 159 and 160, but the slide valve member 162, as shown in Fig. 6, has been moved to its lefthand position by an operator manipulating a pilot valve 163, which is normally urged to the position opposite to that shown in Fig. 6 by a return spring 164. However, in the position shown in Fig. 6, the pilot valve 163 has its ports 165 and 166 interconnected and also has its ports 167 and 168 interconnected. Thus, fluid under pressure from the main supply pipe 153 will pass through ports 166 and 165 of pilot valve 163 through port 169 of the main valve 161 and fluid in the left end of the main valve 161 will escape through a port 170 in the main valve 161 and ports 167 and 168 in the pilot valve 163 to the main return pipe 157.

With the main valve 161 in the position shown in Fig. 6, fluid under pressure through ports 158 and 159 of main valve 145 will be directed to the upper end of the cylinder 48, as pointed out hereinbefore, and will also be directed through a port 171 in the main valve 161, at this time interconnected with port 160, to the lower end of the cylinder 48. Thus, the fluid under pressure from the main supply pipe 153 will be directed to opposite sides of the piston 53 and the difference in effective area of the opposite sides of the piston will result in the piston being moved more rapidly by the differential pressure exerted thereon than would be true if the valve 161 and pilot valve 163 were left in their normal positions. This rapid movement is imparted to the piston 53 in order to insure that the plunger 74 will reach its proper position in the mold chamber 23 before the ram 25 reaches the position shown in Fig. 6 in order that the exhaust system will have time to withdraw any entrapped air from the molding chamber before the ram 25 begins to compress the ceramic material. As soon as the plunger 74 is properly seated in the mold chamber 23, as shown in Fig. 6, the pilot valve 163 may be released to interconnect ports 165 and 168 and ports 166 and 167 thereof for shifting the slide valve member 162 to the right (Fig. 6), whereby the full pressure of the fluid driven by pump 151 will be applied to the upper end of the piston 53.

The lower ram 25 operates under control of a pilot valve 180 and a main valve 181 and, in the position shown, the pilot valve 180 will connect the source of fluid under pressure from the main supply pipe 153 through ports 182 and 183 to the left end of the main valve 181. Simultaneously with the supplying of fluid under pressure to the left end of the main valve 181, ports 184 and 185 of pilot valve 180 will permit the right end of the main valve 181 to be exhausted by

connecting the small cylinder at the right end of the valve 181 to the main return pipe 157. When fluid under pressure is admitted to the left end of the valve 181, a slide valve member 186 will shift to the right (Fig. 6) to interconnect ports 187 and 188 and to connect ports 189 and 190. The port 188 is in communication with pipe 33 and port 189 is in communication with pipe 35. Therefore, when the slide valve member 186 is shifted to the position shown in Fig. 6, fluid under pressure will be supplied to the lower end of the cylinder 137, and the fluid in the upper end of the cylinder 13 will be permitted to flow back to the pump 151 through pipe 157. As long as the ceramic material 86 is under compression between the plunger 74 and the ram 25, as shown in Fig. 6, the two opposing forces will tend to compact the slug of ceramic material between the ram and plunger. As soon as the slug is compacted, and this will occur in a definite length of time with the pressure exerted by the pistons 53 and 27 being a known amount, the position of the pilot valve 144 may be shifted by raising the screen 111, thereby to raise the plunger 74.

A complete understanding of the invention may be had by reference to the following brief description of the mode of operation thereof. A charge of ceramic material to be compressed may be placed in the hopper 94 and with the screen 111 in the position shown in Fig. 1, that is, in its raised position, the hopper 94 may be swung over into position directly in alignment with the cavity in the mold chamber 23 and, thereupon, the handle 105 may be manipulated to transfer the charge of material to be compressed into the mold chamber. As soon as the charge is in the mold chamber, the hopper may be swung back to the position shown in the full lines in Fig. 3 and the screen 111 may be moved to its downward position, where it will be latched in place by the latch 120. As the screen 111 is shifted to its downward position, the actuating arm 140 carried thereby will shift the pilot valve 144 to the position shown in Fig. 6, thereby to supply fluid under pressure to the right end (Fig. 6) of the main valve 145, causing the slide valve member 155 to shift from its right hand position to its left-hand position, as shown. When the slide valve member 155 shifts to the position shown, fluid under pressure from the main supply pipe 153 will be directed to the upper end of the cylinder 48 through pipe 54. In order to increase the speed of movement of the piston 53 and ram 74, the pilot valve 163 may be shifted to the position shown against the action of the spring 164, thus by a differential action to supply fluid under pressure to the lower end of the cylinder 48, as well as the upper end thereof. In this manner, the speed of operation of the piston 74 will be materially increased. As soon as the plunger 74 is positioned, as shown in Fig. 6, the interior of the mold chamber 23 will be subjected to a vacuum due to the operation of the stem 79, which will lift the head 78 (Fig. 4) off of the seat 81 and thus any air which may be entrapped in the mold chamber 23 will be exhausted therefrom. When the plunger 74 reaches its lowest position, as shown in Fig. 6, the pilot valve 163 may be released and the spring 164 will then return the valve to its normal position to enter ports 166 and 167 and the ports 165 and 168, respectively. This will result in the shifting of the slide valve member 162 of main valve 161 to the position opposite to that shown in Fig. 6, and a high degree of

pressure will then be exerted against the piston 53. After the plunger 74 has thus been seated in position extending in the molding chamber 123, pilot valve 180 may be operated to shift main valve 181 to the position shown in Fig. 6, thus to supply fluid under pressure through pipe 33 to the lower end of the cylinder 13, thereby to compress the charge of ceramic material 86 between the ram 25 and the plunger 74, the slide valve member 186 being shifted to the position shown in Fig. 6 when pilot valve 180 is in the position shown in Fig. 6.

After a charge of ceramic material 86 has been compressed into a slug in the molding chamber, the plunger 74 may be moved away from the compressed slug by raising the screen 111, which will shift the pilot valve 144 to a position opposite to that shown in Fig. 6, thereby interconnecting ports 146 and 148 and ports 147 and 149 of the pilot valve. With this condition prevailing, fluid under pressure will be supplied to the left end (Fig. 6) of the main valve 145 and, therefore, fluid under pressure will be supplied through ports 158, 159 and 160 of valves 145 and 161 to the underside of the piston 53, the spring 164 having returned pilot valve 163 to a position opposite to that shown, thereby having caused slide valve member 162 to shift to the opposite position from that shown. While the plunger 74 is moving upwardly, the pilot valve 180 may be left in the position shown, but the piston 27 will not move the ram 25 upwardly at this time due to the resistance of the slug of ceramic material 86 against upward movement. Therefore, the plunger 74 will move upwardly rapidly until it reaches its uppermost position, at which time the pressure in the system builds up and the piston 27 will start to move upwardly again, thereby to strip the compacted slug from the molding chamber 23. After the slug has been pushed out of the molding chamber of the ram 25 and removed, the pilot valve 180 may be rocked to the position opposite to that shown to cause the main valve 181 to shift to the position opposite to that shown, thereby to return piston 27 to its lowermost position and the apparatus will now be in condition to receive another charge of ceramic material to be compacted therein.

What is claimed is:

1. In a molding press, a molding chamber, a plunger for sealing one end of the molding chamber, a ram for compacting material against the plunger in the molding chamber, sealing means encircling the plunger and engageable with a surface of the molding chamber to define an evacuating chamber communicating with the molding chamber, a suction means, and a valve carried by the plunger for connecting said suction means to the evacuating chamber to evacuate entrapped air from the molding chamber.

2. In a molding press, a molding chamber, a plunger for sealing one end of the molding chamber, a ram for compacting material against the plunger in the molding chamber, means on the plunger automatically operable when the plunger enters the chamber for evacuating entrapped air from the chamber including cooperating means on the molding chamber and plunger forming a sealed passage encircling the plunger and communicating with the molding chamber, a poppet valve having a stem for engaging and opening the valve when the plunger enters the chamber, and a vacuum line normally closed by the poppet valve, said valve serving, upon operation, to connect said passage with the vacuum line.

GEORGE L. CHERRY.
CHARLES C. VEALE.
